(21) Appl. No.: **29/244,969**

The ornamental design for a front bezel for a computer
enclosure, as shown and described.

(22) Filed: **Dec. 16, 2005**

DESCRIPTION

(30) **Foreign Application Priority Data**

Sep. 23, 2005 (CN) 200530070383

FIG. 1 is a perspective view of a front bezel for a computer
enclosure showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and
FIG. 7 is a bottom plan view thereof; and
FIG. 8 is a perspective view thereof being mounted to a
computer enclosure wherein the computer enclosure shown
in broken lines is for illustrative purposes only and forms no
part of the claimed design.
